MAGNETIC THREAD CLEANER

Nicholas Stoddard, Durham, N. C.

Application June 1, 1937, Serial No. 145,856

1 Claim. (Cl. 28—64)

This invention relates to magnetic thread cleaners and has for an object to provide a device of this character having novel magnetically controlled means for severing the thread at the 5 feeler blades when a knot, slub, nib, waste and the like is encountered.

A further object is to provide a device of this character which will be formed of a few strong, simple and durable parts, which will be inexpensive to manufacture, and which will not easily get 10 out of order.

With the above and other objects in view the invention consists of certain novel details of construction and combinations of parts hereinafter 15 fully described and claimed, it being understood that various modifications may be resorted to within the scope of the appended claims without departing from the spirit or sacrificing any of the advantages of the invention:

20 In the accompanying drawing forming part of this specification,

Figure 1 is a front elevation of a magnetic thread cleaner constructed in accordance with the invention.

25 Figure 2 is a top plan view of the cleaner.

Figure 3 is an end elevation of the cleaner looking toward the permanent magnet.

Figure 4 is an end elevation of the thread cleaner looking toward the feeler blades.

30 Referring now to the drawing in which like characters of reference designate similar parts in the various views, 10 designates a supporting plate having a pair of "Porcelain" guide eyes 11 adjustably mounted thereon by screws 12. The thread is drawn through these eyes as usual by the tractive effort of any suitable thread using or winding machine.

The knot responsive means comprises a detector or feeler lever 13 which is pivoted intermediate its ends on a substantially rectangular frame 14, the pivot pin 15 of the lever being disposed near one end of the frame, as best shown in Figure 2. The lever extends beyond the path of the thread through the porcelain eyes and is 40 equipped with a pair of feeler blades 16 adapted to receive the moving thread loosely but adapted to be forced bodily from normal position by frictional contact with an imperfection in the thread such as a knot, slub, nib, or other enlargement and 45 rock the lever on its pivot.

50 The feeler blades are attached to the lever by a bolt 17 having a shim thereon to space the blades at a predetermined distance apart, depending upon the size of the thread to be cleaned.

55 The opposite end of the lever is equipped with an armature 18 which overlies pole pieces 19 of a permanent horse shoe magnet 20 which is carried by the frame 14. The pull of the magnet on

the armature accelerates pivotal movement of the feeler lever 13 when an imperfection is encountered by the feeler blades to quickly actuate the thread severing mechanism which will now be described.

An angular dog 21 is pivotally mounted in the frame 14 underneath the feeler lever. The pivot pin 22 of the dog is passed through one leg of the dog that extends substantially parallel with the lever while the other leg of the dog extends 10 perpendicular to the lever and is disposed substantially midway between the pivot of the lever and the armature as best shown in Figure 1. The dog normally hooks over a keeper plate 23 which extends across the rear end of a knife blade 24. 15 The blade projects through a slot 25 in one end of the frame 14 and is slidably supported inside of the frame by a pin 26.

A rod 27 is secured to the plate 23 and to a 20 downwardly bent end portion of the blade 24 and sleeved upon the rod is a helical spring 28 which is normally under compression when the dog 21 is engaged with the keeper plate 23. When the feeler blades 16 encounter an imperfection in the 25 thread too large to pass between them, the blades will be moved bodily and the movement of the lever will be accelerated by the attraction of the armature to the permanent magnet.

Movement of the lever is transmitted to the 30 dog to rock the dog from engagement with the keeper plate. Instantly the spring expands and forces the knife outwardly to sever the thread. The rod 27 projects outwardly through an end wall of the frame 14 and is equipped with a grip 35 29 by means of which the knife blade may be withdrawn sufficiently to permit the dog to hook over the keeper plate and maintain the knife in cocked position ready for the next operation.

From the above description it is thought that 40 the construction and operation of the invention will be fully understood without further explanation.

What is claimed is:

A thread cleaner comprising a support, thread guides on the support, a feeler lever pivoted on 45 the support, feeler blades on the lever responsive to imperfections encountered in the thread to rock the lever, an armature on the opposite end of the lever, a magnet on the support adapted to attract the armature and accelerate rocking 50 movement of the lever, a spring pressed knife slidably mounted on the support, and a dog pivoted on the support and normally holding said knife cocked, said dog being adapted to be struck and dislodged by rocking movement of the lever 55 to free the knife for severing the thread contiguous to said imperfections.

NICHOLAS STODDARD.
